UNITED STATES PATENT OFFICE.

ERNST GLANTZBERG, OF SPRINGFIELD, MASSACHUSETTS.

HEATING SYSTEM.

SPECIFICATION forming part of Letters Patent No. 787,748, dated April 18, 1905.

Application filed April 11, 1904. Serial No. 202,573.

To all whom it may concern:

Be it known that I, ERNST GLANTZBERG, a citizen of the United States of America, and a resident of Springfield, in the county of Hampden and State of Massachusetts, have invented 5 certain new and useful Improvements in Heating Systems, of which the following is a full, clear, and exact description.

This invention relates to improvements in 10 heating apparatus in which steam or hot water is employed as the heating agent, and although in the description hereinafter given the term "steam" is generally employed, it is to be understood that the word steam is to 15 be used interchangeably with hot water, one being the equivalent of the other so far as the capabilities of the present invention are concerned.

The object of the invention is to provide a 20 heating system in which there may be as many individual heaters as desired, all supplied from a single boiler or source of steam, with arrangements whereby the steam may be controlled, preferably, at a point remote from the individual heaters, so that the steam may enter 25 only one heating-chamber of one or more of the heaters or both heating-chambers thereof, all to the end of providing adequate heat for any apartment or apartments, and more 30 or less according to the temperature conditions and with no liability of overheating, and thus the steam-supply for the heating purposes will be economically applied and the occupant of the apartment to be heated 35 need not concern himself with the control or regulation of the steam, although in addition to the steam-controlling arrangements operable in the boiler-room or remote from the apartment to be heated valves individual to 40 the respective heaters or series of them may be provided for opening and closing the heaters to and from the passage of steam thereinto.

The parts and arrangements composing the 45 steam-heating system are hereinafter fully described, in connection with the accompanying drawings, and set forth in the claims.

In the drawings, Figure 1 is a view in the 50 nature of a diagram, showing series of heaters in several buildings or apartments all

connected with a single source of steam-supply having valves and valve-controlling arrangements appertaining to each series of heaters and the different sets of heating-chambers therein. Fig. 2 is a sectional view of 55 the lower portion of a heater or radiator such as may be advantageously embodied in the present heating system. Figs. 3 and 4 are perspective representations of special valve-operating means provided for the aforementioned radiator.

In the drawings, A A represent a series of heaters or radiators each having a compartment or heating-chamber *a* and a compartment or heating-chamber *b* therein, one thereof being separate or divided from the other.

B represents a steam-boiler from which a steam-pipe C runs to connection with the main heating-chambers *a* of the several heaters A A, this pipe being of course branched 70 within the building or room at which the series of heaters are located for the respective connections, and adjacent the several heaters is a pipe D, branched from the main steam-pipe C, the same having continuations or 75 branches connecting into the secondary heating-chambers *b* of the several radiators A.

F and G represent valves in the main steam-pipe C and the branched steam-pipe D, having their locations between the junction of the two pipes and the chambers of the heaters with which these pipes are respectively connected, these said valves having diaphragm-motors *f* and *g* of a very common and well-known description operably subject to 80 the pressure of a motor fluid, such as compressed air, and the pipes *f*² *g*² are connected, respectively, with the diaphragm-cases of the valve-motors *f* and *g* and with the receiver of an air-compressor E, each of these 85 pipes having a manually-operated controlling-valve *f*³ and *g*³, respectively. In addition to and back of the motor-controlled valves *f* and *g* the main pipe C and branch D preferably have provided therein hand-operated valves *h* and *i*. By opening the valve 90 *f*³ in the air-pipe *f*² the motor *f* for the main steam-pipe valve F may be operated to open such valve and permit an access of steam into the main heating-chamber of each of the 95

100

- heaters A A of the series, or instead the valve g^3 in the air-pipe g^2 may be opened for giving an access of steam into the other compartment b of each of the heaters of the series 5 accordingly as considerable or a lessened degree of heat is desired, and where a maximum heat is desired both valves may be simultaneously opened, and by the provision of the valves h and i , back of the motor-controlled 10 valves F and G, it becomes possible to prevent, as might be desirable at times, any steam entrance into either of the compartments of the heaters of the series, even although the motor-controlled valves might be 15 opened.
- It has not been deemed necessary herein to illustrate the usual return-conduits for the steam condensation, it being understood that proper provision therefor is to be made.
- 20 Description thus far has been given in connection with the series of heaters A comprised in the left-hand group and with the connections and appliances therefor, and next to the right thereof is shown another group of heaters A², having heating-chambers a^2 and b^2 therein, divided or separated the one from the other, and the branch C² of the main steam-pipe C and subbranches of the branch C² connecting the main steam-pipe C with the set of 25 heating-chambers a^2 in the several radiators A², while a branch pipe D² of the aforesaid pipe branch C² connects the said branch C with the set of heating-chambers b^2 in the several radiators A², the primary branch C² and 30 the secondary branch D² having between their junction and the respectively connected radiators, the valves F²G² having valve-operating motors f² and g², with one of which motors an air-pipe has connection, said pipe being 35 controlled by its other end connected with the air-compressor E, a hand-operated valve j³ being provided in such pipe j, and a pipe g⁴ has connection with the diaphragm-case of the valve-controlling motor g², provided for the secondary branch D², such pipe having, primarily, a connection with the receiver of the air-compressor, and in the example here illustrated, by being connected as a branch of the aforementioned pipe g². By having at least 40 one of the valve-controlling motors appertaining to the pipe connections for the second group of heaters A² pipe-connected with the compressed-air receiver by a pipe independent of and additional to either of the pipes f² or g² it becomes possible at a point of control 45 remote from the group of heaters A² to establish heat in the heating-chambers of the radiators A² in a high or moderate degree, as may be desired, and for a different period of time 50 than that for which heat may be established in the left-hand group of heaters, and in extension of the capabilities incidental to this invention a right-hand group of heaters A³ is shown, for which a branch C³ of the main steam-pipe C has connections through proper

subbranches, and the motor-controlled valve F³ for the pipe C³ has connection to the motor thereof the air-pipe k, the same also having primarily a connection with the air-compressor receiver, and, as shown, by having such pipe k connected into one of the air-pipes (here the one g²) operatively arranged in connection with the motors controlling the valves for the steam-supply pipes of the other group or groups of heaters. 75

As an example of the availability of the present invention for supplying economically steam or hot water heat to various customers, the left-hand group of heaters may be those comprised in a hotel or dwelling, the middle 80 group of heaters those in an office-building, and the right-hand group of heaters those comprised in a warehouse. By opening the valves f³ and g³ or only opening the valve g³ the hotel may be heated, say, for the whole day of 85 twenty-four hours at a maximum or an intermediate degree of heat, as may be required, and the warehouse, the heating-chambers in which are of less heating capacity than those in the heaters A, may be heated for the same 90 length of time at the considerably lower degree as predetermined in the installation of the heaters, and the heaters A² in the office-building may be controlled to heat in a maximum degree—say for ten hours—or during 95 the time of occupancy of the building by the opening of the valve j³, when by closing such valve the further heating by the group A² will be under the control of the air-valve g³, so that if the conditions are such that the secondary heaters of the secondary chambers b of the heater group A should and are receiving steam the secondary chambers b² of the heating group A² will also receive steam, and without attempting to describe or illustrate 100 the variability and extent of and to which the invention may be carried out it is desired to bring clearly to notice that differently-located sets of heaters may be all supplied from a common heating source and so controlled that at the place of location of each set the heating may be more or less high, as desired, and the periodicity of the heating in the place of installation of one set of heaters may be different from that at the place of installation of 105 the other set of heaters, although one controller for the valve-motors of pipes pertaining to several of the groups may be utilized to establish a moderate degree of heat in the heaters of several or all of the groups, the attainment of a maximum heat in any of the groups being by the manipulation of the controller for the valve-motor of the steam-supply pipe or pipe branch pertaining to the 110 heaters of the group in which the maximum heat is required.

Under certain phases of this invention novel arrangements exist, even although separate heaters or separate heating-chambers are provided only in one set or group in a given place, 115

apartment, or building, so long as there is provided thereto a source of steam-supply, (which might be in the same building,) a main steam-pipe being provided to connect the 5 steam-supply with one set of the heating-chambers, while a branch thereof connects the other set of heating-chambers, and a valve of suitable description is provided in the pipe or pipes connected with the different sets of heating-chambers located between the junction of the main steam-pipe and the branch thereof. Nevertheless the extension of the idea of means whereby different sets or groups of heaters at different locations all supplied from 5 a common source of steam through a main feed-pipe and branches thereof together with controlling means whereby the degree of heat in the different groups of heaters and the period in which such degree of heat may be maintained variable in the different groups is novel and very desirable, as thereby enabling the most economical supplying of heat to different consumers according to their varied needs, giving a maximum of heat where desired and a materially lessened degree of heat where desired, with no overheating at one place and under heating at another, and all with a most economical utilization of the steam in the steam-supply plant, and in a manner whereby no attendant at the place or places to be heated is required to control or regulate the heat thereat.

While the means for variably controlling the heat at the different locations is through the 5 medium of the motors for the valves, having air-pipe connections with a compressed-air receiver and valves for opening and closing the air-pipes to render the valve-motors active or passive, as here particularly illustrated and described, other valve-operating means may be depended upon than those just mentioned, whether the same be operable manually, mechanically, electrically, or thermostatically.

In Fig. 2 a form of heater or radiator is represented having the heating-chambers *a* and *b* therein connected by a passage *m*, having a valve *n* therefor, which may be usually closed, but which may be opened when desired, so that instead of having a radiator with divided 5 chambers dependent for its supply on respectively provided steam-pipe connections the radiator may be transformed into one adapted to receive steam for heating throughout its entire space, and therefore by providing individual radiators in a group of the kind last mentioned a person in a given room may acquire a full volume of steam in the particular radiator even although but one of the steam-feeding pipes connected thereto and to other 5 heaters in the same group is opened, and in order that the valve *n* may be operated only by a person properly conversant with the steam regulation the stem *n*² for the valve which screw-threads at *n*³ through a gland *n*⁴ 5 has its extremity *n*⁵ constructed to be engaged

only by a special key or wrench *o*, the same having recesses or wards *o*², specially formed to engage the projections *n*⁶ on the valve-stem extremity *n*⁵; said extremity being inclosed within a socketed shield *p*.

Having thus described my invention, what I claim, and desire to secure by Letters Patent, is—

1. In a heating system, a plurality of groups of heaters one or more thereof comprising separate chambers in the heaters of each group, a common source of steam-supply, a main steam-pipe connected with one set of the chambers of one of the groups of heaters, and having a branch connected with the other set of chambers of such group, said steam-pipe and its branch having respectively motor-controlled valves, and independently-operable means controlling said motors, a branch of the main steam-pipe connected with a set of 80 the heating-chambers of another of the heater groups, having a motor-controlled valve therefor, and motor-actuating means operable independently of the means for controlling the first-named valve-controlling motors. 90

2. In a heating system, a plurality of groups of heaters, comprising separate chambers in the heaters of each group, a common source of steam-supply, a main steam-pipe, connected with one of the chambers of one of the groups of heaters, and having a branch connected with the other set of heating-chambers of such group, said steam-pipe and its branch having respectively motor-controlled valves, and independently-operable means controlling said motors, a branch of the main steam-pipe connected with a set of the chambers of another of the heater groups, having a motor-controlled valve therefor, and motor-actuating means operable independently of the means 100 for controlling the first-named valve-controlling motors, and a steam-pipe branch of the last-named branch connected with the other set of chambers of the said other heater group and having a valve and controlling-motor 110 therefor, said motor being operated by the means for operating one of the first-named motor-controlling valves. 105

3. In a heating system, a plurality of groups of heaters, one or more thereof comprising 115 separate heating-chambers in each group, a common source of steam-supply, a main steam-pipe, connected with one set of heating-chambers of one of the groups of heaters, and having a branch connected with the other set of heating-chambers of such group, said steam-pipe and its branch having respectively motor-controlled valves, a branch of the main steam-pipe connected with a set of the heating-chambers of another of the heater groups, 120 having a motor-controlled valve therefor, a source of motor fluid, independent pipe connections between said source and the respectively provided valve-controlling motors. 125

4. In a heating system, a group of heaters 130

A, comprising separate heating-chambers a b , and a group of heaters A^2 having chambers a^2 , a common source of steam-supply, a main steam-pipe C connected with the set of chambers a , and having a branch D connected with the other set of chambers b , said steam-pipe and its branch having respectively the valves F and G with motors f and g , a branch C^2 of the main steam-pipe C connected with the set A^2 of the heating-chambers, having a valve F^2 and a controlling-motor f'' therefor, a compressed-air reservoir, and the air-pipes f^2 g^2 and j connecting said reservoir respectively with the valve-motors f^2 g^2 and f'' and valves f^3 g^3 and j^3 individually provided in the said air-pipes.

5. In a heating system, a plurality of groups of heaters A and A^2 comprising separate heating-chambers a b and a^2 b^2 respectively, a common source of steam-supply, a main steam-pipe C connected with the set of chambers a , and having a branch D connected with the set

of chambers b , and having a branch D connected with the other set b of the chambers, said steam-pipe and its branch having respectively the valves F and G with motors f and g , a branch C^2 of the main steam-pipe C connected with the set of heating-chambers a^2 having a valve F^2 and a controlling-motor f'' therefor, and a branch D^2 of pipe branch C^2 connected with the set of heater-chambers b^2 , having a controlling-motor g'' therefor, a compressed-air reservoir, the air-pipes f^2 g^2 and j connecting said reservoir respectively, with the valve-motors f^2 g^2 and f'' , and valves f^3 g^3 and j^3 individually provided in the said air-pipes, and a branch of the air-pipe g^2 connected with said valve-motor g'' .

Signed by me at Springfield, Massachusetts, in presence of two subscribing witnesses.

ERNST GLANTZBERG.
